R. W. G. STUTZKE,
PROCESS FOR DESICCATING FLUID SUBSTANCES.
APPLICATION FILED JUNE 8, 1916.

1,350,247.

Patented Aug. 17, 1920.

UNITED STATES PATENT OFFICE.

RICHARD W. G. STUTZKE, OF CHICAGO, ILLINOIS, ASSIGNOR TO CROWN MALTOSA COMPANY, OF CHICAGO, ILLINOIS, A CORPORATION OF ILLINOIS.

PROCESS FOR DESICCATING FLUID SUBSTANCES.

1,350,247.

Specification of Letters Patent. Patented Aug. 17, 1920.

Application filed June 8, 1918. Serial No. 102,441.

To all whom it may concern:

Be it known that I, RICHARD W. G. STUTZKE, a subject of the Emperor of Germany, residing at Chicago, in the county of 5 Cook and State of Illinois, have invented a new and useful Improvement in Processes for Desiccating Fluid Substances, of which the following is a specification.

My invention relates to the art of desiccating fluid substances carrying solids in solution or in suspension therein. The object of the invention is to provide an improved process for accomplishing such desiccation and an improved form of apparatus for carrying out the process. More particularly, my present invention relates to the method of desiccation described in my prior Patent No. 1,215,889, February 13, 1917.

20 The invention will be more fully understood from the following detailed description and from the drawings accompanying and forming part of the same.

In the drawings, Figure 1 is a diagrammatic vertical sectional view, partly in elevation, of a simple form of desiccating apparatus constructed in accordance with my invention; and Fig. 2 is a top plan view of the same.

30 It may be said, by way of introduction, that my present process of desiccation, like that of my prior patent referred to, involves the continuous use of the same desiccating medium, this medium being circulated and re-circulated through a practically closed system of conduits, nothing entering the system save the fluid to be desiccated, and nothing leaving it save the desiccated product and the moisture removed therefrom. The only energy used in the process (aside from radiation and leakage losses) is, therefore, that relatively small amount required for the continuous operation of the pumps, together with those heat units 40 actually required to evaporate the moisture from the product to be desiccated, at the working pressure. The process of my present application differs from that of my prior application in that my present process 45 is concerned particularly with the desiccation of substances which would be injured by subjection to temperatures substantially exceeding 212° F. The apparatus employed for carrying out the new process is correspondingly modified.

Referring more particularly to the drawings, the numeral 10 designates the desiccation-chamber of my apparatus, which, as shown, is arranged horizontally, the fluid to be desiccated being introduced by a spray-nozzle 11 at one end of the chamber. The desiccating medium is supplied to the chamber 10 through an inlet conduit 12 which has interposed therein a heater 13, shown conventionally as a vertical casing inclosing a gas-burner 14 which heats the exterior walls of a bank of tubes 15 through which the desiccating medium passes. Beyond the heated section 13 the conduit 12 is return-bent for connection to the outlet side of a cyclone dust-collector 16.

At its outlet end the desiccating-chamber 10 is connected with the central inlet 17 of a centrifugal circulating pump 18 which may be driven by any approved means, not shown, and which has its tangential outlet 19 discharging into the tangential inlet 20 of the cyclone dust-collector 16. The bottom of the dust-collector is provided with a self-packing, four-armed dumping-gate 19', the wings of which at all times close the outlet but permit the discharge of the powder collected by revolution of the gate, as is well understood.

An exhaust-pump, illustrated as of the rotary type, and designated 21, has its inlet side connected by a conduit 22 with some portion of the desiccation apparatus, preferably with the inlet-pipe 12.

The operation of the apparatus above described is as follows. The burner 14 having been put in operation, the circulating-pump 18 and the vacuum-pump 21 are started, whereby the air within the apparatus is caused to travel through the heating-pipes 15, inlet 12, desiccation-chamber 10, dust-collector 16, and thence by the pipe 12 back to the heater. Simultaneously, by the action of the vacuum-pump 21 a certain proportion of the air is exhausted from the closed system, with reduction of pressure therein. When the pressure has been reduced by the predetermined amount, for instance, to seven pounds per square inch absolute, and the temperature of the circulating medium has reached a point above the boiling-point of water at the pressure existing within the apparatus, the fluid to be desiccated is sprayed into the chamber 10 through the nozzle 11. The liquid is instantaneously 105 sprayed into the chamber 10 through the nozzle 11. The liquid is instantaneously 110

evaporated and converted into superheated steam, and the dried particles of solid material are carried along to the collecting chamber 16, where they are deposited. The introduction of this additional fluid into the closed system and its evaporation therein will cause a rise in pressure within the system which must be relieved by the vacuum-pump 21. As the apparatus continues to operate, the air within the system will be gradually displaced by superheated vapor resulting from the evaporation of the water or other fluid injected into the system, so that under normal operating conditions the entire system will be filled with the superheated vapors of the solution to be desiccated, this superheated mass serving as a desiccating medium, absorbing heat from the heater 13, and utilizing this heat for the evaporation of the fluid introduced into the system. By the action of the vacuum-pump 21, the pressure within the system is constantly maintained at the predetermined figure, which must be sufficiently low so that the temperature required for giving a substantial degree of superheat to the circulating medium will be so low that the desiccated product will suffer no injury. By employing sufficiently low pressures, the principle of desiccation by a circulating mass of superheated vapors may be applied to the most unstable and easily injured organic substances, it being quite possible to dry economically according to this method at temperatures not exceeding 100° F. where superheated steam is used as the desiccating medium. Very much lower temperatures may be employed, as is quite obvious, where the fluid introduced has a lower boiling-point or vapor-tension, as, for instance, in the desiccation of alcoholic solutions. It should further be noted as characteristic of the invention that it is possible to condense and collect the superheated vapors vented from the desiccation

system, which is of especial advantage where a menstruum such as alcohol, naphtha, or other valuable liquid carries the solids to be dried. Such condensation may even be advantageous where aqueous solutions are employed, since by the use of a properly proportioned condenser the required vacuum may be obtained without any pump or with the use of a small condenser pump only.

While I have shown and described in considerable detail one specific embodiment of my invention and the exact manner in which the process is carried out in such embodiment, it is to be understood that this showing and description is illustrative only and for the purpose of making my invention more clear, and that I do not regard the invention as limited to these details nor to any of them, except in so far as I have included such limitations within the terms of the following claims, in which it is my intention to claim all novelty inherent in my invention as broadly as is possible in view of the prior art.

What I claim as new and desire to secure by Letters Patent is:—

1. The process of evaporating liquids, which consists in spraying the liquid into an atmosphere entirely of its own vapor, circulating said atmosphere and superheating it during its circulation, and exhausting the evaporated liquid from the circulating system at such a rate as to maintain a sub-atmospheric pressure therein.

2. The process of evaporating liquids, which consists in spraying the liquid into an atmosphere entirely of its own vapor, circulating said atmosphere and super-heating it during its circulation, and exhausting the evaporated liquid from the circulating system at such a rate as to maintain a sub-atmospheric pressure therein, and collecting the desiccated solids.

RICHARD W. G. STUTZKE.
